GRINDING MILL

Filed March 31, 1930

UNITED STATES PATENT OFFICE

RUDOLF P. JUGEL, OF DENVER, COLORADO, ASSIGNOR TO AMERICAN BALL MILL COMPANY

GRINDING MILL

Application filed March 31, 1930. Serial No. 440,404.

My invention relates to grinding mills, and particularly to lining sections for shells thereof. The mill heads and the construction and arrangement of other parts shown in 5 the present drawing are described more in detail and claimed in my co-pending application Serial No. 440,403 filed March 31, 1930.

An object of the invention is to provide 10 lining sections for a grinding mill that are individually removable without disturbing the other sections.

A further object is to provide a lining of 15 the character mentioned, the sections of which are held in place without the use of bolts or nuts.

Another object of the invention is to increase the strength of the shell without increasing the amount or changing the kind of 20 material therein and yet provide a shell suitable for the lining hereinabove referred to.

It is to be understood that my grinding mill is suitable for use with any grinding medium, whether balls, rods or pebbles.

25 Novel details of construction and novel combinations and arrangements of parts will appear in the course of the following description. In the drawing, like reference characters designate similar parts in the several 30 views.

Figure 1 is an elevation, partly in section, of a grinding mill containing an embodiment of the invention.

Figure 2 is an enlarged, broken section taken 35 on the line 2—2 of Figure 1.

Figure 3 is a broken section taken on the line 3—3 of Figure 2.

Figure 4 is a broken section taken on the line 4—4 of Figure 2.

40 Figure 5 is a plan view of the rear surface of a lining section.

Referring more in detail to the drawing, the reference numeral 6 designates standards for the support of the mill.

45 The mill comprises a shell 7 having heads 8 and 9. The heads have integral trunnions 10 and 12 respectively of reduced diameter. Liners 13 and 14 are supported in the trunnions 10 and 12 respectively. The liner 13

50 has an internal screw 15 for feeding material

to the interior of the shell 7. A scoop, partly shown at 16, feeds material to the inlet trunnion 10. The trunnions are mounted for rotary support in bearings 17 on the standards. A spout 18^a on the outlet trunnion 12 communicates with bore 18 of the liner 14 for the discharge of material. 55

Since per se the elements mentioned in the preceding paragraph, with the exception of the shell 7, form no part of the present invention, they will not be described in further detail. 60

The heads 8 and 9 have sectional liners composed of sections 19 and 20, the latter being slotted or otherwise apertured to provide grates, all of which are described more in detail in my application of the above-mentioned serial number. 65

The shell has channels 21 provided by external, longitudinal ribs 22. These ribs are 70 also useful in strengthening the shell without increasing the amount or changing the kind of material. Flanges 23 on the heads are bolted to flanges 24 at the ends of the shell. Bolts 25 are also used to fasten in place a 75 gear 27 by means of its web 26.

A sectional lining is provided for the shell, a section of which is shown at 28 in Figure 5. Each liner section has spaced lugs 29 at one edge, which are comparatively short in 80 length. Along the opposite edge of the same face of the liner is a somewhat longer lug 30, corresponding in length and position to the space between the lugs 29.

The face of the liner section, opposite to that carrying the lugs, has a ridge or rib 31, which strengthens the section and assists in lifting material during rotation of the mill. 85

The liner sections are arranged in longitudinal alignment in the shell, with their lugs in the channels 21. The lugs, however, do not fill the channels, but leave spaces between adjacent sections. Blocks or fillers 32 of wood or other compressible and/or expandable material, are placed flat in the channels for fastening the sections in place. These blocks are approximately the length of the space between lugs 29 on the same liner section, the width of the space between lug 30 and the opposite side of the channel 21, when the sections 90

95

100

are in position, and the thickness of the projecting length of the lugs.

Filler blocks 33 also of wood or other compressible and/or expansible material provide 5 wedges or fillers between the series of aligned sections to hold same in position. The blocks 32 are flat in the channels between the lugs 30 and the opposite sides of the channels and between the lugs 29 of the adjacent section, as 10 best shown in Figure 3. The blocks 33 are placed or driven in the spaces between the series of sections and abut against the blocks 32.

The grate sections 20 have slots 34 that connect with passages 35 formed by flanges 36 on 15 the grate sections. The passages 35 are connected with the bore 18 by transverse bores 37 that pour material on to a cone 38.

In the use of the invention, material is fed 20 into the mill by the scoop 16. The screw 15 then carries the material into the shell, where it is pulverized by balls, rods or pebbles in the well-known manner. The pulverized material moves through the slots 34, into the passages 35, through the transverse bores 37, on 25 to the cone 38, through the bore 18, and then is discharged by the spout 18a.

When removing a section, the bordering wedges 33 on either side are removed. The section is then removed and replaced by 30 another without disturbing the other sections in the shell. The sections fit snugly around the portions of the shell between the channels and the lugs of the sections project into the channels. The blocks 32 in the channels are 35 arranged between lugs 29 of one section, and between lug 30 of the adjacent section and the opposite wall of the channel.

Then wedge blocks 33 are placed between 40 the sections to abut against the adjacent blocks 32. Continued operation of the mill tightens the liners, as the hammering effect of the falling material and grinding medium wedge the blocks 33 tighter.

Changes may be made in the details of construction and arrangement without departing from the spirit of the invention.

What I claim and desire to secure by Letters Patent is:

1. A grinding mill comprising a channeled 50 shell, a sectional lining for the shell, sections of the lining having lugs in the channels, and fillers between the lugs and walls of the channels, holding the lugs in the channels.

2. A grinding mill comprising a channeled 55 shell, a sectional lining for the shell, sections of the lining having lugs in the channels, adjacent sections having spaced lugs and lugs opposite the spaces, and fillers between the spaced lugs, engaging walls of the channels 60 and the other lugs.

3. A grinding mill comprising a channeled 65 shell, a sectional lining for the shell, sections of the lining having lugs in the channels, adjacent sections having spaced lugs and lugs opposite the spaces, fillers between the spaced

lugs engaging walls of the channels and the other lugs, and secondary fillers between adjacent sections.

4. A grinding mill comprising a channeled shell, a sectional lining for the shell, sections 70 of the lining having lugs in the channels, adjacent sections having spaced lugs and lugs opposite the spaces, fillers in the channels between the spaced lugs, engaging walls of the channels and the other lugs, and secondary 75 fillers outside the channels, between adjacent sections.

5. A grinding mill comprising a channeled shell, a sectional lining for the shell, sections 80 of the lining having lugs in the channels, adjacent sections having comparatively short, spaced lugs and having comparatively long lugs opposite each other's spaces, and fillers between the spaced lugs, the long lugs and the channel walls, holding the sections in place. 85

6. A grinding mill comprising a channeled shell, a lining having sections aligned in rows at opposite sides of the channels, opposite sections of the rows having spaced lugs and lugs opposite the spaces respectively, and 90 fillers in the channels between the spaced lugs, the other lugs and the walls of the channel.

In testimony whereof I hereunto affix my signature.

RUDOLF P. JUGEL.
